KNIFE UNIT

Sigurd Clausen, Brooklyn, N. Y., assignor to International Cigar Machinery Company, a corporation of New Jersey

Original application April 29, 1936, Serial No. 76,932. Divided and this application November 13, 1940, Serial No. 365,423

3 Claims. (Cl. 146—159)

This invention relates to cigar machines. This application constitutes a division of my co-pending application Serial No. 76,932, filed April 29, 1936, which became Patent No. 2,276,289 on March 19, 1942, and the main object of the subject matter of this application is to provide a novel knife unit which is suitable for severing tobacco sections from a stream of filler tobacco. With this and other objects not specifically mentioned in view, the invention consists in certain constructions hereinafter fully described and claimed.

Referring to the drawing which forms a part of this specification and in which like characters of reference indicate the same or like parts:

Fig. 1 is an end elevation of the knife unit; Fig. 2 is a side elevation of the same; and Fig. 3 is an enlarged sectional view of the knife unit.

From a column or stream of filler tobacco, which may be suitably compacted, a tobacco section is severed by a knife 255. The knife 255 (Figs. 1, 2 and 3) is ground to provide a cutting edge thereon and mounted in a frame 256 suspended from studs 257 carried by the projecting arms 258 of the upper tie-bracket 259. Bracket 259 and a lower tie-bracket 260 are clamped on the vertical slide-rods 261 which are guided in hubs 262 of bracket 205 and in bearings 264 adjustably attached to the frame of the machine. On a forked lug 265 of tie-bracket 260 is pivotally mounted one end of a rod 266 which is connected with a cam lever 267 fulcrumed on a cross shaft 268. An upright arm 269 of cam lever 267 carries a cam follower 270 which engages a cam track in cam 272. The knife 255 (Fig. 1) may be formed of two separate sections which are fastened to frame 256 by screws passing through a clamp bar 273 and threaded into the frame 256, the bar being recessed to receive the stems 274 of two adjusting screws 275 which assure correct vertical positioning of the knife. On a bracket 276 is adjustably supported a block 277 carrying a ledger plate 278, bracket 276 being equipped with adjusting screws 279 which permit vertical adjustment of ledger plate 278 for aligning the same with guide 202 and guide 280. The member 280 is fastened to the top of the bracket 276 and forms a continuation of the guide 202. On each end of bracket 205 is pivoted an arm 281 which is equipped with a roller 282 engaging the knife frame 256. Rollers 282 are held in constant engagement with frame 256 by means of springs 283 which are seated in recesses provided in bracket 205 and arm 281, and in this manner the

tongues 284 (Fig. 3) of the knife, which are guided in slots 285 of frame 256 are held against ledger 278. The knives used heretofore had an appreciable thickness and consequently removed thick slices of filler tobacco in severing the tobacco sections, which slices were wasted. By using a very thin knife having a beveled cutting edge in accordance with my invention, no tobacco is wasted during the cutting operation.

By pressing the tongues of the knife against the ledger plate, in accordance with the invention, the knife is continuously maintained in the proper relation to the ledger plate to sever the tobacco section most efficiently.

It will be noted that the clamp bar 273 stiffens the knife, which may have a thickness such that it is capable of distortion and may be warped in the hardening process, and maintains it in alignment with the ledger plate.

The invention above described may be varied in construction within the scope of the claims, for the particular device selected to illustrate the invention is but one of many concrete embodiments of the same. The invention therefore, is not to be restricted to the precise details of the structure shown and described.

What is claimed is:

1. In a cigar machine having a ledger plate, the combination with a vertically reciprocable frame, a relatively thin flat knife of a thickness such that it will shear tobacco sections from a mass of tobacco without punching out tobacco slices from the mass and is capable of distortion, said knife having downwardly extending tongues at its margins, a clamp bar fastening said knife to said frame and extending across the width thereof, and means arranged to guide the margins of said knife during the descent of said support, said means including spring pressed members for continuously pressing said tongues against the ledger plate during the ascent and descent of said support.

2. In a cigar machine having a ledger plate, the combination with a vertically reciprocable support, of a flat knife fastened to said support, said knife having downwardly extending tongues at its margins and having a cutting portion which is of a thickness such that it will shear tobacco sections from a mass of tobacco without punching out tobacco slices from the mass and is capable of distortion and provided with a beveled cutting edge, and means arranged to guide said tongues and continuously press them against the ledger plate during the ascent and descent of the support.

3. In a cigar machine, the combination with a ledger plate, of a support reciprocable vertically toward and away from said ledger plate, a flat knife mounted on said support and coacting with said ledger plate to shear a tobacco section from a mass of tobacco, said knife being sufficiently thin to shear the tobacco section without punching out tobacco slices from said mass in the shearing operation, and said knife being provided with tongues extending downwardly from its

5 margins to engage said ledger plate continuously while said support approaches and recedes from the ledger plate, and yielding means continuously engaging said tongues and acting to maintain said tongues in constant engagement with the ledger plate as the knife descends to sever the tobacco section and while it ascends to initial position.
